DESIGN FOR A DRESS ORNAMENT OR SIMILAR ARTICLE

Louis Merkler, New York, N. Y., assignor to Geller
Scallopine & Novelty Co., Inc., New York, N. Y., a corporation of New York

Application May 16, 1938, Serial No. 77,207

Term of patent 3½ years

To all whom it may concern:

Be it known that I, Louis Merkler, a citizen of the United States, with residence in the county of Bronx, city and State of New York, with a post office address at No. 307 West 38th Street, in the Borough of Manhattan, city and State of New York, have invented a new, original, and ornamental Design for a Dress ornament or Similar Article, of which the following is a specification, reference being had to the accompanying drawing, forming part thereof, in which

Figure 2 is a side elevation of the dress ornament or similar article forming my design, as applied to a background.

I claim:

The ornamental design for a dress ornament or similar article, as shown and described.

LOUIS MERKLER.
